Primary Examiner — Wendy L Arminio*Assistant Examiner* — Mary Claire Nemeth(74) *Attorney, Agent, or Firm* — Oliff PLC(57) **CLAIM**

The ornamental design for a coil component as shown and described.

DESCRIPTION

FIG. 1 is a front elevational view of a coil component, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof; and,

FIG. 7 is a front, left-side, top perspective view thereof.

The broken lines depict parts of the coil component that form no part of the claimed design.
